GEAR SHIFTING CONSOLE FOR A BICYCLE

Keizo Shimano, 81 Midorigaoka, Minami-cho, 3-chome,
Sakai, Osaka, Japan, and Norio Sato, 414 Takosono-
cho, Suita, Osaka, Japan

Filed Dec. 6, 1967, Ser. No. 9,667

Claims priority, application Japan Aug. 11, 1967

Term of patent 7 years

U.S. Cl. D90—1
Int. Cl. D12—14

FIG. 4

FIG. 3

FIG. 6

FIG. 5

FIG. 1 is a front view of a gear shifting console for a bicycle embodying our new design.

FIG. 2 is a back view thereof.

FIG. 3 is a top-plan view thereof.

FIG. 4 is a bottom-plan view thereof.

FIG. 5 is a right side view thereof, and

FIG. 6 is a left side view thereof.

What we claim is:

The ornamental design for a gear shifting console for a bicycle, substantially as shown.
